US0D1076064S

(12) **United States Design Patent** (10) **Patent No.:** **US D1,076,064 S**
(45) **Date of Patent:** **** May 20, 2025**

(54) **AUTOMATED DRUG DELIVERY DEVICE**

(71) Applicant: **INSULET CORPORATION**, Acton, MA (US)

(72) Inventors: **Derek Rund**, Springboro, OH (US); **Josh Haldeman**, Loveland, OH (US); **Mary Friedl**, Covington, KY (US); **Michael Palmisano**, Cincinnati, OH (US); **Tony Guard**, Union, KY (US); **Jeffrey Barnes**, Medford, MA (US); **Ayden Henson**, Arlington, MA (US); **David Seward**, Seattle, WA (US); **Steven Cardinali**, Tewksbury, MA (US); **Matthew Alles**, Mooresville, NC (US); **Robert Sanzone**, Sudbury, MA (US)

(73) Assignee: **INSULET CORPORATION**, Acton, MA (US)

(**) Term: **15 Years**

(21) Appl. No.: **29/934,211**

(22) Filed: **Mar. 25, 2024**

(57) **CLAIM**

The ornamental design for an automated drug delivery device as shown and described.

DESCRIPTION

FIG. 1 is a top, front, right side perspective view of an automated drug delivery device, showing our new design; FIG. 2 is a front elevation view thereof;

FIG. 3 is a rear elevation view thereof;

FIG. 4 is a right elevation view thereof, the left elevation being a mirror image of the left elevation; and,

FIG. 5 is a top plan view thereof.

The broken lines showing an adhesive pad depict environmental subject matter and form no part of the claimed design. The bottom is flat and unornamented, is not shown in the drawings, and forms no part of the claimed design.

1 Claim, 5 Drawing Sheets
